TRAIN-CONTROL SYSTEM.

1,118,891.

Specification of Letters Patent. Patented Nov. 24, 1914.

Application filed July 1, 1912. Serial No. 706,939.

To all whom it may concern:

Be it known that I, JOEL AMES, a citizen of the United States of America, residing at Montrose, Iowa, have invented a certain 5 new and useful Train-Control System, of which the following is such a full, clear, and exact description as will enable any one skilled in the art to which it appertains to make and use the same, reference being had 10 to the accompanying drawings, forming part of this specification.

My invention relates to electric train control systems and particularly to circuit arrangements adapted for use in connection 15 with a track which is divided into insulated sections or "blocks".

It is the object of my invention to produce a system by means of which a train is constantly protected against trains coming 20 from either direction and one which will be at once simple and reliable in operation.

Broadly, my invention consists in providing an arrangement of circuits whereby a train controlling circuit, including means 25 for controlling any desired signal or brake controlling devices on the train, is constantly maintained as the train advances along the track. A local circuit, or circuits, on the train may be so arranged that when 30 the train controlling circuit is interrupted on account of the too close approach of another train, or through a broken wire, or a defective battery or connections, a warning signal or the air-brake, or both, will operate. 35

Referring to the drawings, Figure 1 represents the circuit arrangements for a single track road in which it is necessary to protect a train both from head-on and rear end 40 collisions. Fig. 2 shows the circuit arrangements which may be used on a double track road where it is necessary to protect against rear end collisions only. Fig. 3 is an enlarged view showing the local circuit on 45 the train and the portion of the train controlling circuits which is carried by the train.

The track 1, 2, is divided into insulated blocks or sections 43, 44, 45, 46, 47 and 48. 50 Extending along the track is a contact member 3, also divided into insulated sections, preferably of the same length as the track sections. This contact member may be either in the form of a third rail, or may be

a trolley wire located conveniently near the 55 track. If desired, both a third rail and a trolley wire may be provided and either used as the contact member when desired. The rails of each track section are in circuit with the battery 4 and with track relays 60 such as illustrated at 5. When no train is on a block, the battery current causes the relays to attract their armatures as shown at 7. The sections of rail 1 are each connected to a conductor 12 through an armature of a relay, and each section of the contact member 3 is connected to the conductor 11, also through an armature of a relay. In case no telephone is used, the sections of both the track rails and the contact member 65 70 may be connected to a single conductor, as in Fig. 2. In Fig. 1, each track section is connected to an armature of a relay in circuit with rails of the second block to the left, and the sections of the contact member 75 3 are in circuit with an armature of a relay which is connected to the second block to the right. The train carries a contact shoe, or wheel, 41 adapted to constantly bear on the contact member 3 as the train advances. 80 The contact shoe is carried on an insulated support and is connected through a battery 25 and a relay 21 to a truck 19. It will be seen that, by this arrangement, connection is established between one rail of the track 85 and the contact member or third rail. A local circuit is carried on the train, which includes the battery 23, the bell 22, the electro-magnet 26 and the armature of magnet 21. This local circuit is normally open and 90 is only closed when failure of the current in the train controlling circuit, which always includes the magnet 21, allows the armature of this magnet to fall or be retracted. 95

As previously stated, the armatures of the various track relays are held in the attracted positions when no train is on a block. The trucks of a train, however, short-circuit the battery 4 and thus permit the armatures 100 to be retracted under the influence of springs (not shown), and thus open the circuits of which these armatures are part. In Fig. 1, trucks 19, 20, represent a train going in one direction and trucks 52, 53, represent 105 a train going in the opposite direction. It will be seen that the first of these trains is partly in one block and partly in another

and the result is that the armatures of the relays 5 and 6 are released. The trucks of the other train are both in the same block and the armatures of the magnet 8 only are released. Assuming for the moment that the train 52, 53, is several blocks removed from the train 19, 20, and that the armatures of the magnet 8 are, therefore, closed, a train controlling circuit for the train 19, 20, 5 may be traced as follows: beginning with the track rail 1, through the truck 19, and the portion of the circuit on the train as shown in Fig. 3, to contact shoe 41, a section of the contact member 3, one armature of 10 the magnet 8, to the conductor 11, to the conductor 12, and then back to the rail 1, through conductor 50 which is connected to the conductor 12. Similar circuits may be traced for every position of the train 19, 20, 15 it being understood that the wheels of the train and the contact shoe always make contact with the end of one section of the track or contact member before they pass out of contact with the preceding section. The 20 train 19, 20, in the position shown, causes the armature of the relay 6 to be released, thus making an opening in two circuits, one of which includes the section of the contact member in block 43, and the other a rail 25 of block 47, and thereby make it impossible for a following or a meeting train to establish a complete circuit when it reaches these blocks. This is illustrated in Fig. 1, where it appears that no circuit is established 30 through train 52, 53, because the train 19, 20, renders the relay 6 inoperative, permitting its armature to break the circuit which includes the track rail of block 47. Train 35 52, 53, is thereby warned of the presence of 40 the other train and may be brought to a stop by means which will now be described.

It will be understood that my system of train controlling circuits can be used with any desired system of cab signals or automatic stopping devices. In the arrangement illustrated, if, for any reason, the battery 25 cannot send the current through the magnet 21, the armature of this magnet falls and this closes a local circuit containing 45 the bell 22 and the air-brake controlling the magnet 26, which operates to open the air valve 27 and thereby stop the train without the intervention of the engineer. When a train is moving slowly, however, it is not 50 necessary that it be automatically stopped when the train controlling circuit fails and I, therefore, provide means to avoid this. A centrifugal device 28 operated from the axle 55 19 by means of a belt or chain 31, controls an air valve 29. With this arrangement, until the speed of the train exceeds a certain value, the valve 29 will be closed and when this valve is closed, opening the valve 27 will not set the brakes because no air is permitted to exhaust from the train pipe 30.

This centrifugal device may, for example, be set so that the electric system cannot operate to stop the train unless the speed exceeds five (5) or six (6) miles an hour.

Again referring to Fig. 1, it will also be 70 noted that when the truck 53 entered the block 47, it caused the armatures of the magnet 8 to be released and thereby opened the train controlling circuit that extended through the train 19, 20, by way of the section of the contact member adjacent to block 45. The local circuit of this train then also became operative to warn its engineer and to stop the train. It will thus be seen that both trains may be automatically stopped by 75 my system, and that rear end as well as head-on collisions will be prevented, all trains maintaining a protected zone which extends at least the full length of a block both to the front and rear. These blocks, 80 course, may be of any desired length.

As a matter of convenience, in disposing of the third or contact rail at crossings, in case a rail is used, I may provide a second contact shoe located at a convenient place on 90 the train and separated from the forward contact shoe by a distance greater than the width of the crossing and thereby continuously maintain the train controlling circuit while at the same time placing the contact 95 member out of the way of crossing traffic.

In Fig. 2, the magnets 34 to 38 inclusive have only one armature and these armatures are in circuit with a section of the contact member or third rail 3. A track rail of 100 each block and a section of a contact member of each block are each connected to conductor 40. It will be noted that the forward train represented in this figure permits the armature of the relay 36 to be retracted, thus making it impossible for the following train to establish a complete circuit when it reaches the block 44. This arrangement of circuits is designed for a double track road and each train maintains 105 a protracted zone only in the rear. 32 is a semaphore that may be placed at stations and, by means of the switch 18, the train controlling circuit which includes the section of the contact member in block 45 is 110 opened and thus, not only is a visual stop signal displayed, but the automatic stop apparatus is also placed in operation. If it is desired to permit the train to slow up for orders, but to run past the stations without 115 stopping, the operator may close the hand switch 33 and thus permit the formation of a complete train controlling circuit when the train reaches block 45, regardless of the fact that the switch 18 is open. 14 and 15 120 represent station telephones which are connected to the main despatcher's wire 13, and these telephone circuits are in transformer relation at 16 and 17, for example, with the train controlling circuits, and in each train 125 130

controlling circuit, the telephone 24 carried on the train and connected in parallel with the battery 25 will be included. It is thus possible for communication to be established between the moving train and the station, or the despatcher's office, at any time.

Referring to Fig. 1, the train controlling circuits established by train 52, 53, when in the position shown, may be traced as follows: from truck 52, through armature of relay 6 (this armature would be in closed position except for the presence of train 19, 20) to conductor 12, conductor 11, armature of relay 10, section of third rail in block 47 and then through the contact shoe and train back to truck 52.

My system is designed to afford a maximum degree of safety in that the normally operative circuits are maintained in closed condition and a broken rail or wire, defective or exhausted batteries, and sluggish or inoperative relays will cause the warning to be given. The train can then proceed cautiously until it reaches a point where the train controlling circuits are properly established again. Thus, instead of the safety of the train depending upon the proper condition of the controlling apparatus, as is the case in many other systems, a defect in the apparatus will have the same effect as the proximity of another train. A train will be warned or stopped when approaching a broken rail or burned or washed out bridges.

Modifications in the arrangement of the conductors and in other details of the apparatus may, of course, be made within the scope of my invention. I do not desire, therefore, that it be limited except as set forth in the appended claims.

Having fully described my invention, what I claim as new and desire to secure by Letters Patent of the United States is:

1. In a train control system, the combination with a track divided into insulated sections, of a contact member extending along said track and also divided into insulated sections corresponding in length to adjacent track sections, electromagnets, each in circuit with the track rails of a section, two

conductors extending along the track and connected at one end, a plurality of partial circuits for controlling trains, each including a portion of each of said conductors, a section of the contact member and a switch controlled by an electromagnet, and a telephone circuit connecting stations and in transformer relation with the train controlling circuits.

2. In a train control system, the combination with a track having one rail divided into insulated sections or blocks, of a contact member extending adjacent to said track and also divided into insulated sections of substantially the same length as the track sections, circuit controlling devices, each in circuit with a part of each track rail, a plurality of partial circuits for controlling trains, each including a section of an insulated track rail and a section of the contact member, and means governed by each of the circuit controlling devices for making an opening in two partial train controlling circuits, one of which includes the section of the contact member in the second block in one direction, and the other the section of the insulated track rail in the second block in the opposite direction from the block in which the controlling device is connected.

3. In a train control system, the combination with a track having one rail divided into insulated sections, of a contact member extending along said track and also divided into insulated sections, circuit controlling devices, each in circuit with a part of each track rail, two conductors extending along the track and connected at one end, a plurality of partial circuits for controlling trains, each including a portion of each of said conductors, a section of the contact member and a switch controlled by a circuit controlling device.

In testimony whereof, I have hereunto set my hand and affixed my seal in the presence of the two subscribing witnesses.

JOEL AMES. [L. s.]
